UNITED STATES PATENT OFFICE.

CARL E. TIDEMAN, OF WORCESTER, MASSACHUSETTS, ASSIGNOR OF ONE-HALF TO
VERNER G. ANDERSON, OF WORCESTER, MASSACHUSETTS.

HAND VALVE-GRINDER.

1,306,932.

Specification of Letters Patent. Patented June 17, 1919.

Application filed July 17, 1918. Serial No. 245,326.

To all whom it may concern:

- Be it known that I, CARL E. TIDEMAN, a citizen of the United States, residing at Worcester, in the county of Worcester and 5 State of Massachusetts, have invented certain new and useful Improvements in Hand Valve-Grinders, of which the following is a specification, reference being had therein to the accompanying drawings.
- 10 This invention relates to a hand valve grinder. The object of the invention is the construction of a simple and efficient device or machine that can be constructed at a minimum expense and which will be compact in structure and can be readily transported.
- 15 With this and other objects in view my invention comprises certain novel constructions and combinations of parts as will be clearly illustrated in the accompanying drawings, specifically described in the following specification and more particularly pointed out in the appended claims.

In the drawings:

- 20 Figure 1 is a vertical sectional view of a device constructed in accordance with the present invention, while

25 Fig. 2 is a sectional view taken on line 2—2 of Fig. 1, and looking in the direction of the arrows.

30 Fig. 3 is a horizontal sectional view taken on line 3—3 of Fig. 1, and looking in the direction of the arrows.

35 Fig. 4 is a horizontal sectional view taken on line 4—4 of Fig. 2, and looking in the direction of the arrows.

Fig. 5 is a perspective view of the crank sleeve.

40 Fig. 6 is a perspective view of the cap plate and showing the pivoted bifurcated member carried thereby.

Fig. 7 is a perspective view of the auxiliary link.

Referring to the drawing by numerals, 1
45 designates the casing, and 2 the cap of my device or machine. The cap 2 is provided with a suitable handle 3, and in the cap, and formed in alignment with each other, are journals 4 and 5. The journal 4 is comparatively long, and supports one end of a manually-driven shaft 6, the other end of the shaft 6 extending through the journal or bearing 5, and is connected to the crank arm 7, which arm is provided with a grip 8.
50 Securely fastened to the driven shaft 6, is a

primary gear 9. The shaft 6 is prevented from moving outwardly from within the journal bearing 4, by means of the locking collar 10.

While the cap 2 is provided with the 60 primary journal or bearing 4, the casing 1 is provided with the lower or auxiliary bearing 11 and the intermediate bearing or journal 12. An auxiliary gear 13, provided with an integral shaft 14, is supported upon 65 the intermediate bearing 12, and a sufficient amount of frictional resistance is exerted, through the medium of set screw 15^a, to keep the shaft 14 in a satisfactory working position upon the bearing 12.

70 A disk 15 is integral with the outer end of the auxiliary gear 13, and this disk carries a pin 16, on which pin is mounted the primary link 17, and the outer or lower end of link 17 is mounted on the auxiliary pin 18, 75 which pin 18 is attached to the lower end of arm 19. The arm 19 is integral with the outer end of crank sleeve 20, which sleeve is journaled upon the shaft 21, carried by the lower or auxiliary bearing 11. Depending 80 from and integral with the crank sleeve 20 is a sleeve 22, and in the lower end of sleeve 22 is positioned the pin 23, which pin 23 is integral with the bifurcated primary cap 24. An auxiliary bifurcated cap 25 is pivotally 85 mounted through the medium of the rivet-like member 26, upon the cap plate 27, which plate 27 is fastened to the upper end of the valve-tool carrying shaft 28.

90 Pivotally mounted, at 29, upon the shaft 28, is the valve tool 30, adapted to engage the valve 31, as shown in Fig. 1.

The primary and auxiliary bifurcated caps 24 and 25 are connected by means of an auxiliary link 32, which link has its apertured 95 ends registering with the apertures in the caps 24 and 25, and through the registering apertures are passed the fastening rivets or members 33, Fig. 1.

100 The operation of the device is as follows: Rotary motion is imparted to the primary gear 9, through the medium of the crank 7 and shaft 6, and thence rotary movement is imparted to the auxiliary gear 13, causing the primary link 17 to be raised and lowered and resulting in an oscillatory movement of the arm 19, of the crank sleeve 20, which in turn oscillates or swings back and forth the depending sleeve 22 of crank sleeve 20, as clearly indicated by the dotted 110

lines in Fig. 2. This oscillation or swinging of the crank sleeve and its integral members results in a partial rotation of the valve-tool carrying shaft 28, which in turn im-
5 parts a partial rotary movement to the valve 31, being worked upon, thereby enabling the operator to manually grind the valve in a very efficient manner, by the use of a device constructed in accordance with the present
10 invention.

What I claim is:

1. A valve grinder comprising a casing provided with a cap, a manually driven primary gear carried by said cap, said casing provided with bearings, an auxiliary gear meshing with the primary gear and supported upon one of the bearings in the casing, a crank sleeve positioned contiguous to the other bearing, means supporting said crank sleeve upon said last-mentioned bearing, said crank sleeve provided with an arm and an integral depending portion, means connecting the arm of the crank sleeve with the auxiliary gear, a tool-carrying shaft journalized upon said casing, and means connecting the integral depending portion of the crank sleeve and the tool-carrying shaft.
20
2. A valve grinder comprising a casing, a tool-carrying shaft journalized upon said casing, a plate secured to the upper or inner end of said shaft, a bifurcated cap pivotally mounted on said plate, another bifurcated cap contiguous to said first-mentioned cap, means pivotally connecting said caps, a crank sleeve provided with an extension co-
25 operating with one of said bifurcated caps, means pivotally mounting said crank sleeve
30
3. A valve grinder comprising a casing and a cap, said cap provided with a pair of alined bearings, one of said bearings substantially one-half the width of the cap, a shaft extending through said bearings, a primary gear secured to said shaft against
35 said last-mentioned bearing, a valve-tool carrying shaft carried by said casing, and means connected to said shaft and said primary gear for driving said shaft when said primary gear is rotated.
4. A valve grinder comprising a casing and a cap, said cap provided with a pair of alined bearings, one of said bearings substantially one-half the width of the cap, a shaft extending through said bearings, a primary gear secured to said shaft against
40 said last-mentioned bearing, a valve-tool carrying shaft carried by said casing, and means connected to said shaft and said primary gear for imparting a swinging or oscillatory movement to the valve for actuating the crank sleeve and the tool-carrying shaft.

upon said casing, and means for imparting a swinging or oscillatory movement to said crank sleeve for imparting a rotary motion 40 to said valve-carrying shaft.

3. A valve grinding device comprising a casing, a valve-carrying shaft extending through one end of said casing, a cap plate secured to the inner end of said shaft, a bifurcated cap provided with means extending through said plate and pivotally securing said cap thereto, a crank sleeve provided with an integral arm and with an integral depending sleeve, a bifurcated cap provided with a pin extension, the pin extension extending into the depending sleeve of the crank sleeve, a link between said caps, means pivotally connecting the ends of said link to said caps, and means connected to the arm of said crank sleeve and being adapted to impart a swinging or oscillatory movement to the arm for actuating the crank sleeve and the tool-carrying shaft.

4. A valve grinder comprising a casing and a cap, said cap provided with a pair of alined bearings, one of said bearings substantially one-half the width of the cap, a shaft extending through said bearings, a primary gear secured to said shaft against
60 said last-mentioned bearing, a valve-tool carrying shaft carried by said casing, and means connected to said shaft and said primary gear for driving said shaft when said primary gear is rotated.
70

In testimony whereof I hereunto affix my signature.

CARL E. TIDEMAN.
